UNITED STATES PATENT OFFICE.

MICHAEL M. FREDEL, OF BROOKLYN, AND WILLIAM BOSANKO, OF NEW YORK, N. Y.

TICKET FEEDING MACHINE.

Application filed December 17, 1924. Serial No. 756,618.

To all whom it may concern:

Be it known that we, MICHAEL M. FREDEL and WILLIAM BOSANKO, both citizens of the United States, and residents, respectively, of the borough of Brooklyn, county of Kings, city and State of New York, and Richmond Hill, borough of Queens, city and State of New York, have invented an Improvement in Ticket-Feeding Machines, of which the following is a specification.

Our present invention relates to a ticket feeding machine, and while not limited to that particular use the apparatus made in accordance with our invention is especially designed for feeding a ticket, premium, coupon, or notice printed on a slip of paper to a receptacle or carton before the same is moved or conveyed to a filling apparatus by which cereal or other similar substances are placed in the package. In packaging cereals and like materials it is customary to place the cartons or boxes on an endless conveyor to which, by any suitable mechanism, an intermittent movement is imparted whereby the cartons successively are brought to position beneath the filling apparatus and then moved on to devices for sealing the package. As hereinbefore stated, it is often desirable for many purposes to insert a ticket, coupon, or notice printed on a slip of paper into the carton before the same is filled so that when the package is open the ticket or coupon or notice is available for its intended purposes by the consumer. Also as hereinbefore stated, the machine made in accordance with our present invention is especially designed for feeding a ticket or coupon to each of the cartons or boxes as the same are moved by the conveyor to the filling apparatus, and our improved ticket feeding machine is so designed that a ticket or coupon is automatically fed and delivered so as to drop into a carton or box as the same is brought to rest on its way to the filling apparatus.

To this end in carrying out the invention, we preferably employ a tray or receptacle adapted to receive and contain a plurality of tickets preferably placed on edge, together with means for advancing the tickets, a device for removing one ticket at a time and feeding the same to a delivery device by which each ticket is rapidly fed from the machine and permitted to drop into a carton or other receptacle. The ma-

chine also includes tension devices by which the tickets are maintained in position in the tray under a predetermined pressure, devices for preventing the feeding of more than one ticket at a time, and also means for maintaining a portion of the tickets in position in the tray while the ticket supply in the tray is being replenished, as will be hereinafter more particularly described.

In the drawing:

Fig. 1 is a side elevation of a ticket feeding machine made in accordance with our present invention.

Fig. 2 is a plan of the same.

Fig. 3 is an enlarged section taken on line 3—3, Fig. 4.

Fig. 4 is an end elevation.

Fig. 5 is an enlarged section taken on line 5—5, Fig. 4.

Fig. 6 is a partial elevation illustrating one of the adjustable bearings for one of the feed rolls, and

Fig. 7 is a perspective view of a plate which may be employed in maintaining the tickets in position while filling the tray.

In referring to the drawings, it will be seen that in carrying out our invention the machine or apparatus comprising the same may be mounted on a suitable base 10 and a post or standard 11. This means of mounting the apparatus, however, is only diagrammatic as the mechanism comprising the invention may be supported in the necessary position for operation in any suitable way. In carrying out the invention we employ a tray or container 12 for receiving and holding a plurality of tickets or coupons or similar slips of paper upon which a notice of a predetermined nature is printed, and this tray comprises a bottom 13, side walls 14, 15, and an end wall 16, the tray being made of any suitable material, preferably rectangular, and consequently closed at one end, open at the opposite end, and also open at the top. Adjacent the closed end of the tray the base thereof is provided with sets of spaced lugs 17 and 18, the function of which will be hereinafter specified.

Within the tray we employ a follower 19. This preferably comprises a plate of metal or other material and this in oppositely disposed positions at the sides thereof is fitted with trunnions 20 and 21 which pass through and move in longitudinal slots 22 provided for this purpose in the side walls 110

14, 15 of the tray. The follower is actuated by weights 23 and 24 which are connected to the trunnions 20 and 21 by means of chains 25 and 26 passing over pulleys 27, 28, 29 and 30 respectively. Corresponding ends of these chains 25 and 26 are connected to the weights 23 and 24 at one end thereof, while the opposite ends of these chains are connected in any suitable manner to the 10 trunnions 20 and 21. The weights 23 and 24 are provided at their opposite or lower ends with T's 31 and 32. These T's are suitably secured in the ends of the weights and are employed as hangers to support the 15 weights upon the lugs 17 and 18 when it is desired to move the follower 19 toward the closed end of the tray in order to fill the tray with the tickets or coupons.

The machine or apparatus also includes 20 a carriage which is mounted to swing and also to reciprocate, the carriage being provided with devices for removing one ticket at a time from the forward end of the pile of tickets when the carriage is reciprocated 25 and the carriage is maintained revolubly against the forward end of the tickets so as to coact with the follower and the means for moving the same to maintain the tickets under a predetermined pressure while being moved forward in the tray. This carriage comprises side rails 33, 34, connected at their upper ends by a bolt 35 and a sleeve or spacer 36, which parts are maintained in position relatively to one another by nuts 37 or otherwise. These side rails are also connected by a tie bolt and spacer 38. The carriage is pivotally mounted at one end of a lever 39 which is operated by means of a rod 40. At a suitable position midway the 30 ends of the lever 39 the same is pivotally mounted as indicated at 41 in a bracket 42 suitably attached to the side wall 15 of the tray. The outer end 43 of the lever 39 is pivotally connected to the sleeve 36 so that the carriage may swing thereon and also be reciprocated thereby. The opposite end of the lever 39 is pivotally connected as indicated at 44 to the upper end of the rod 40. This rod is mounted between guide rolls 45 and 46 carried by the side 15 of the tray and also by similar guide rolls 47 and 48 suitably connected to the standard 11. Adjacent its lower end the rod 40 carries a cam wheel 49. This cam wheel 49 bears against a surface of a cam 50 carried by a cam shaft 51 driven as hereinafter specified, and these parts are maintained in their operative positions by means of a spring 52. At its upper end the spring 52 is connected by a bolt 53 or otherwise to the lower extremity of the rod 40, while at its opposite end this spring 52 is connected to a stud bolt 54 or similar device mounted in the base 10.

Fitted in the carriage there is a friction roller 55. This friction roller is mounted

on a shaft 56 on which there is also mounted a ratchet 57 engaged by a pawl 58 pivotally mounted as shown at 59. The pawl is normally maintained in contact with the teeth of the ratchet by a spring 60 adjustably mounted in the tie bolt 38 or otherwise. This friction roller is normally maintained against the outermost ticket or coupon of the tickets or coupons which are placed on edge in the tray and are indicated at 62. 75 The relationship between the friction roller and the pawl and ratchet device is such that when the carriage is moved downwardly the friction roller is prevented from turning so that by and through its frictional contact with the outermost ticket this ticket is moved away from the next succeeding ticket and fed to the delivery rollers hereinafter described. When the carriage moves upwardly on its return movement the friction 80 roller is permitted to turn over the surface of the then outermost ticket so that the position of the same in the tray will not be disturbed.

At the forward end of the tray and extending across the same we provide a plate 63. This plate 63 is secured to the sides of the tray in any suitable manner and at its forward ends the overlapping sides or flanges of the plate extend forwardly of the tray as indicated at 64 and 65 to act as guides for the side rails of the carriage which bear against the inner surfaces of these projections on the plate. As indicated, the plate is maintained in position by means of bolts 66, but as will be understood this manner of securing the plate in position is only illustrative. At the lower ends of the rails of the carriage there are projections indicated at 67 and 68. These projections are connected to weights 69 and 70 by means of chains 71 and 72. The chains are connected at corresponding ends to the upper ends of the weights and at their opposite ends to the projections of the carriage. The chains pass over rollers 73 and 74 respectively so that by means of the weights the carriage is normally maintained in that position revolubly in which the surface of the friction roller 55 is maintained in contact with the surface of the outermost ticket or coupon in the tray. In order to increase the tension exerted by the weights 69 and 70, and therefore to vary the pressure exerted by the roller against the tickets in the tray when the mechanism is operated, we may provide, as indicated, the tension devices which include the pins 75 and 76 connected in the lower ends of the weights 69 and 70 and extending therefrom through spaced projections 77 and 78 on a bracket 79 secured to the standard by means of bolts 80 or otherwise. Beneath the projections 77 and 78, the pins 75 and 76 are provided with springs 81 and 82 which ex-

tend between the under sides of the projections and adjusting nuts 83 and 84 mounted on the screw threaded extremities of the pins 75 and 76. By this construction, as 5 will be understood, in addition to the tension exerted by the weights 69 and 70, the tension and consequent pressure brought to bear against the tickets may be varied as may be necessary under varying conditions 10 in the operation of the apparatus. It will also be understood that in many instances it is not necessary to use these devices for varying the tension exerted against the forward end of the tickets.

15 The machine also includes feed rolls which are indicated at 85 and 86 and are placed directly in the path of the outermost ticket as the same is removed from the forward end of the tickets in the tray. The 20 roll 85 is mounted on a shaft 87 driven from a pulley 88 which may be turned by a suitable belt or otherwise operated from any source of power. The shaft 86 is mounted in bearings 89 and 90 which are carried by 25 brackets 91 and 92 fixed in any suitable manner to a cross bar 93 which is secured to the base of the tray. The feed roll 86 is secured on a shaft 94 and the shaft and this feed roll are driven from the shaft 87 by 30 means of spur gears 95 and 96 or otherwise. As indicated, the spur gear 95 is fixed on the shaft 87 and the spur gear 96 on the shaft 94. This shaft 94 is journaled in bearing blocks 97 and 98 which are adjustable 35 to position so as to fix the feed roll 86 in place relatively to the feed roll 85. As indicated in Fig. 6, the bearing block 98, for example, is provided with slots 99 and 100 through which clamp bolts 101 and 102 pass, 40 while the bearing block, when the bolts 101 and 102 are loosened, may be adjusted and fixed in place by means of an adjusting screw 103 mounted to turn in a lug 104 carried by the side of the tray. The adjusting 45 bolt may be locked in place by means of a nut 105 or otherwise.

On the side of the tray opposite that on which the rod 40 operates, we prefer to employ a bar or rod 106. As indicated, this 50 bar 106 is mounted in a position parallel to the side of the tray by being passed through apertures provided for this purpose in lugs 107. On the bar 106 we employ a sliding bracket 108 which may be fixed in any position along the bar by means of a set screw 109 or otherwise. The sliding bracket 108 extends across the top of the tray and is provided with a slot 110 adapted to receive a plate 111 as indicated in Fig. 7. This sliding bracket and plate are advantageously employed in filling the tray with tickets or coupons. After the tickets have been advanced for any predetermined distance the sliding bracket may be adjusted to that position in which the plate 111 may be passed

through the slot 110 and between the rear-most ticket and the adjacent face of the follower 19. Then, as will be understood, the weights 23 and 24 may be supported on the lugs 17 and 18 and the follower readily moved to the rear end of the tray and a new supply of tickets or coupons placed in the tray after which the weights 23 and 24 may be returned to their normal operative positions being suspended by the chains 25 and 26 and the plate 111 withdrawn from the slot 110. This is done without stopping the carton filling machine.

55 In a central position at the forward end of the tray the plate 63 is provided with a bracket 112. Adjustably mounted in this bracket 112 is a rod 113. The rod 113 may be maintained in any desired position in the bracket by means of a set screw 114 or otherwise. The rod 113 carries a bearing 115 through which an awl or needle 116 passes. This bearing 115 is preferably slit or divided and carries a collar 117 by which and a binding screw 118 the awl or needle 60 after having been adjusted to the necessary position may be clamped and maintained in place therein. This awl or needle is so placed that the point thereof projects appreciably into the tray so as to penetrate one, two or more of the forward tickets or 65 coupons adjacent the upper edge thereof as the same are advanced to the feed and delivery devices in order, as will be understood, to prevent more than one of the tickets or coupons being delivered at one time.

70 In the operation of this apparatus, the same is suitably associated, for example, with a machine for filling cartons or containers with cereal or like materials. These containers, one of which is indicated at 119 75 in Fig. 1 of the drawing, are placed upon an endless conveyor 120 and maintained in position thereon by brackets 121 or otherwise with the open end 122 of each carton or container uppermost. The conveyor is 80 moved intermittently to bring each carton beneath the filling device which operates automatically to supply a sufficient quantity of the cereal or other material to fill the carton. The apparatus comprising our invention is so placed that each time the endless conveyor stops one of the cartons or 85 containers is brought and stopped immediately beneath the delivery rolls 85 and 86. The cam shaft 51 is connected in any suitable manner with the apparatus for filling the cartons so that the cam is timed to operate the rod 40, the lever 39 and the carriage with its friction roller each time the 90 intermittently moving conveyor is stopped. When the carriage is moved downwardly the friction roller is prevented from turning, and being in contact with the outermost ticket carries the same away from the pile 95 and tears the upper edge thereof from the 730

point of the needle 116 and feeds the lower edge of the ticket to the delivery rolls 85 and 86. These delivery rolls are turned at a relatively high speed so that each succeeding ticket or coupon as fed to the rolls is caused to pass rapidly through the same and permitted to drop through the open end 122 of a carton or container 119 before the next movement of the intermittently moved end-
less conveyor.

As will now be understood the tickets or coupons as placed in the tray will be automatically moved forward by the action of the weights 23 and 24 through the chains 15 25 and 26 and the follower 19. This exerts a tension sufficient to feed the tickets forward and to cause the outermost tickets to be punctured by the awl or needle. On the other hand the tension exerted against the 20 tickets in the opposite direction by means of the weights 69 and 70 through the chains 71 and 72 acting through the carriage and the friction roll is adjusted to be just sufficient to maintain the forward ticket in the 25 proper position when moved by the friction roller to be fed to the delivery rolls, and under varying conditions this causes a pressure with which the tickets are maintained in position in the tray, that is adjustable 30 under varying conditions when necessary by the tension adjusting devices including the pins 75 and 76, the springs 81 and 82 coacting with the projections 77 and 78 of the brackets 79 and the adjusting nuts 83 35 and 84. It will also be understood that the adjustment of the feed rolls is necessary in order to insure each ticket passing through the same properly because of the rapidity with which the feed rolls are turned and 40 the likelihood of unevenly feeding the successive tickets if these feed rolls are not in proper adjustment.

We claim as our invention:

1. In a ticket feeding machine, a tray for 45 containing tickets, a pivotally mounted reciprocating carriage, a device mounted in the said carriage for removing one ticket at a time from the tray, means for advancing the tickets in the tray to maintain the 50 foremost ticket in frictional engagement with the said device, and devices for cooperating with the said carriage and the means for advancing the tickets in the tray for maintaining the tickets under a predetermined substantially uniform pressure while 55 being advanced in the said tray.

2. In a ticket feeding machine, a tray for 60 containing tickets, a pivotally mounted reciprocating carriage, a device mounted in the said carriage for removing one ticket at a time from the tray, means for advancing the tickets in the tray to maintain the 65 foremost ticket in frictional engagement with the said device, devices for cooperating with the said carriage and the means for

advancing the tickets in the tray for maintaining the tickets under a predetermined substantially uniform pressure while being advanced in the said tray, and means for preventing the removal of more than one 70 ticket at a time from the container.

3. In a ticket feeding machine, a tray for containing tickets, a pivotally mounted reciprocating carriage, a device mounted in the said carriage for removing one ticket 75 at a time from the tray, means for advancing the tickets in the tray to maintain the foremost ticket in frictional engagement with the said device, devices for cooperating with the said carriage and the means for advancing the tickets in the tray for maintaining the tickets under a predetermined substantially uniform pressure while being advanced in the said tray, means for preventing the removal of more than one ticket 80 at a time from the container, and devices for rapidly delivering each ticket as the same is removed from the tray.

4. In a ticket feeding machine, a tray for containing tickets, a pivotally mounted carriage, means for reciprocating the pivotally mounted carriage, a device mounted in the carriage for removing one ticket at a time from the tray, means for advancing the tickets in the tray and maintaining the foremost ticket in frictional contact with the said device, and means coacting with the said carriage and the said device together with the means for advancing the tickets in the tray for maintaining the tickets under a predetermined substantially uniform pressure while being advanced in the tray.

5. In a ticket feeding machine, a tray for containing tickets, a pivotally mounted carriage, means for reciprocating the pivotally mounted carriage, a device mounted in the carriage for removing one ticket at a time from the tray, means for advancing the tickets in the tray and maintaining the foremost ticket in frictional contact with the said device, means coacting with the said carriage and the said device together with the means for advancing the tickets in the tray for maintaining the tickets under a predetermined substantially uniform pressure while being advanced in the tray, and means for preventing the removal of more than one ticket at a time from the tray.

6. In a ticket feeding machine, a tray for containing tickets, a pivotally mounted carriage, means for reciprocating the pivotally mounted carriage, a device mounted in the carriage for removing one ticket at a time from the tray, means for advancing the tickets in the tray and maintaining the foremost ticket in frictional contact with the said device, means coacting with the said carriage and the said device together with the means for advancing the tickets in the tray for maintaining the tickets under a pre- 130

determined substantially uniform pressure while being advanced in the tray, means for preventing the removal of more than one ticket at a time from the tray, and delivery devices to which each successive ticket is fed and rapidly delivered as removed from the tray.

7. In a ticket feeding machine, a tray for containing tickets, a pivotally mounted carriage, means for reciprocating the carriage, a roller mounted in the carriage, means for advancing tickets in the tray for normally maintaining the foremost ticket in contact with the said roller, means cooperating with the roller for preventing the same from turning when the carriage is moved in one direction to remove the outermost ticket from the tray and permitting the roller to turn on the surface of the next succeeding ticket when the carriage is moved in the opposite direction, and means for coacting with the carriage, said roller mounted therein and the means for advancing the tickets in the tray for maintaining the tickets under a predetermined substantially uniform pressure as the same are advanced in the tray.

8. In a ticket feeding machine, a tray for containing tickets, a pivotally mounted carriage, means for reciprocating the carriage, a roller mounted in the carriage, means for advancing tickets in the tray for normally maintaining the foremost ticket in contact with the said roller, means cooperating with the roller for preventing the same from turning when the carriage is moved in one direction to remove the outermost ticket from the tray and permitting the roller to turn on the surface of the next succeeding ticket when the carriage is moved in the opposite direction, means for coacting with the carriage, said roller mounted therein and the means for advancing the tickets in the tray for maintaining the tickets under a predetermined substantially uniform pressure as the same are advanced in the tray, and means for preventing the removal of more than one ticket at a time from the container.

9. In a ticket feeding machine, a tray for containing tickets, a pivotally mounted carriage, means for reciprocating the carriage, a roller mounted in the carriage, means for advancing tickets in the tray for normally maintaining the foremost ticket in contact with the said roller, means cooperating with the roller for preventing the same from turning when the carriage is moved in one direction to remove the outermost ticket from the tray and permitting the roller to turn on the surface of the next succeeding ticket when the carriage is moved in the opposite direction, means for coacting with the carriage, said roller mounted therein and the means for advancing the tickets in the tray for maintaining the tickets under a pre-

determined substantially uniform pressure as the same are advanced in the tray, means for preventing the removal of more than one ticket at a time from the container, and delivery devices for rapidly delivering each successive ticket as the same is removed from the tray.

10. In a ticket feeding machine, a tray for containing tickets, a pivotally mounted carriage, a roller mounted in the carriage, a follower in the said tray, weight and chain devices for moving the follower to advance the tickets in the tray so as to maintain the foremost ticket in frictional contact with the said roller, means for maintaining the roller in a locked position when the carriage is moved in one direction, means for reciprocating the carriage causing the roller when in its locked position to remove the foremost ticket from the tray, and weight and chain devices cooperating with the said carriage for causing the roller to exert a predetermined pressure against the tickets in the tray, the said pressure being exerted in a direction opposite to that exerted by the said follower in order to maintain the tickets while in the tray under a predetermined pressure.

11. In a ticket feeding machine, a tray for containing tickets, a pivotally mounted carriage, a roller mounted in the carriage, a follower in the said tray, weight and chain devices for moving the follower to advance the tickets in the tray so as to maintain the foremost ticket in frictional contact with the said roller, means for maintaining the roller in a locked position when the carriage is moved in one direction, means for reciprocating the carriage causing the roller when locked to remove the foremost ticket from the tray, weight and chain devices co-operating with the said carriage for causing the roller to exert a predetermined pressure against the tickets in the tray, the said pressure being exerted in a direction opposite to that exerted by the said follower in order to maintain the tickets while in the tray under a predetermined pressure, and means for adjusting the tension exerted by the said roller against the tickets in the tray.

12. In a ticket feeding machine, a tray for containing tickets, a pivotally mounted carriage, a roller mounted in the carriage, a ratchet and pawl device for preventing the roller from turning when the carriage is moved in one direction and permitting the roller to turn on the face of the next succeeding tickets when the carriage is moved in the opposite direction, a follower in the said tray, weight and chain devices for moving the follower to advance the tickets in the tray so as to maintain the foremost ticket in frictional contact with the said roller, means for reciprocating the

carriage causing the roller to remove the foremost ticket from the tray, and weight and chain devices co-operating with the said carriage for causing the roller when held by the said ratchet and pawl to exert a predetermined pressure against the tickets in the tray, the said pressure being exerted in a direction opposite to that exerted by the said follower in order to maintain the tickets while in the tray under a predetermined pressure.

13. In a ticket feeding machine, a tray for containing tickets, a pivotally mounted carriage, a roller mounted in the carriage, a ratchet and pawl device for preventing the roller from turning when the carriage is moved in one direction and permitting the roller to turn on the face of the next succeeding ticket when the carriage is moved in the opposite direction, a follower in the said tray, weight and chain devices for moving the follower to advance the tickets in the tray so as to maintain the foremost ticket in frictional contact with the said roller, means for reciprocating the carriage causing the roller when held by said ratchet and pawl to remove the foremost ticket from the tray, weight and chain devices cooperating with the said carriage for causing the roller to exert a predetermined pressure against the tickets in the tray, the said pressure being exerted in a direction opposite to that exerted by the said follower in order to maintain the tickets while in the tray under a predetermined pressure, and means for pre-

venting the removal of more than one ticket at a time from the tray.

14. In a ticket feeding machine, a tray for containing tickets, a pivotally mounted carriage, a roller mounted in the carriage, a ratchet and pawl device for preventing the roller from turning when the carriage is moved in one direction and permitting the roller to turn on the face of the next succeeding ticket when the carriage is moved in the opposite direction, a follower in the said tray, weight and chain devices for removing the follower to advance the tickets in the tray so as to maintain the foremost ticket in frictional contact with the said roller, means for reciprocating the carriage causing the roller when held by said ratchet and pawl to remove the foremost ticket from the tray, weight and chain devices cooperating with the said carriage for causing the roller to exert a predetermined pressure against the tickets in the tray, the said pressure being exerted in a direction opposite to that exerted by the said follower in order to maintain the tickets while in the tray under a predetermined pressure, means for preventing the removal of more than one ticket at a time from the tray, and delivery rolls for rapidly delivering each succeeding ticket as the same is removed from the tray.

Signed by us this 11th day of December, 1924.

MICHAEL M. FREDEL.
WILLIAM BOSANKO.
